UNITED STATES PATENT OFFICE.

JAMES F. BAILEY, OF COLUMBIA, SOUTH CAROLINA.

WRENCH.

Application filed March 9, 1922. Serial No. 542,399.

To all whom it may concern:

Be it known that I, JAMES F. BAILEY, a citizen of the United States, residing at Columbia, in the county of Richland and State of South Carolina, have invented certain new and useful Improvements in Wrenches; and I do hereby declare the following to be a full, clear, and exact description of the invention, such as will enable others skilled in the art to which it appertains to make and use the same.

This invention has relation to a combination wrench of the type embodying a handle, complementary jaws pivoted to the handle and means for adjusting the jaws and holding them in the required adjusted position.

The invention relates chiefly to the general structure and more particularly to the formation of the jaws and the adjusting mechanism cooperating therewith.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a perspective view of a wrench embodying the invention,

Figure 2 is a side view, the handle section on the near side being removed,

Figure 3 is a transverse section on the line 3—3 of Figure 1, looking in the direction of the arrows,

Figure 4 is a central longitudinal section taken on the line 4—4 of Figure 1, and

Figure 5 is a detail view in perspective of the jaw operating member.

Corresponding and like parts are referred to in the following description and designated in the several views of the drawings by like reference characters.

The wrench comprises a handle which embodies similar or like sections, each section consisting of a cheek portion 1 and a semi-cylindrical portion 2. When the handle sections are assembled, the cheek portions 1 are spaced apart and extend in parallel relation and the semi-cylindrical por-

tions 2 come together and may be secured in any preferred way, as by fastenings 3, which may consist of rivets or bolts, or said sections may be electrically welded or secured in any manner. Each of the handle sections is provided at its rear end with an inner rib 4, whereby to provide a swivel connection between the handle and the adjusting nut 5 by means of which the jaws are moved.

The jaws 6 are of similar or like formation and are mounted upon a pivot 7 which is supported in the cheek portions 1 of the handle. Each of the jaws 6 has a rear extension 8 which is curved in its length, said extensions being laterally spaced and curving in opposite directions to insure like movement of the jaws when adjusting the same.

The operating member for the jaws comprises a head 9 and a threaded stem 10, the latter cooperating with the adjusting nut 5. The head 9 is slideable between the cheek portions 1 of the handle and is provided at opposite ends with opposed lateral flanges 11 which engage the longitudinal edges of the cheek portions 1 to retain the head in position and direct the same in its movement. Similar recesses 12 are formed in opposite sides of the head 9 to receive the curved extensions 8 of the jaws 6. Opposite walls of the recesses 12 are curved to correspond with the curved edges of the extensions 8. The recesses 12 extend in opposite directions to correspond with the extensions 8. Movement of the head 9 lengthwise of the handle effects an opening or a closing of the jaws according to the direction of movement thereof. Rotation of the adjusting nut 5 moves the head 9 lengthwise of the handle.

The adjusting nut 5 is elongated and fits snugly between the semi-cylindrical portions 2 of the handle. An annular groove 13, formed in the outer side of the nut 5 adjacent the rear end thereof, receives the annular rib 4, thereby constituting the swivel connection between the nut and handle. A fingerpiece 14, formed with the nut 5, abuts the rear end of the handle and conforms thereto and is roughened or milled on its outer surface to enable a firm grip to be obtained thereon when rotating the nut 5 to adjust the jaws 6 to the work.

The beaks of the jaws 6 are elongated and are of similar or like formation and are

disposed in the length of the handle. The beaks of the jaws 6 may operate as pliers or as wrench jaws to grip a nut or rod in substantially the same manner as a nut or pipe wrench.

What is claimed is:

1. A wrench of the character specified, comprising a handle consisting of similar or like sections, each of the sections including cheek and semi-cylindrical portions, the cheek portions being spaced and extending in parallel relation, and the semi-cylindrical portions coming together when the sections are assembled, similar or like jaws pivoted between the cheek portions of the handle and having rearwardly curved extensions laterally spaced and projecting in opposite directions, an operating member comprising a head and threaded stem, the head being 20 slideable between said cheek portions and recessed in opposite sides to receive the curved extensions of the jaws, and a nut engaging said threaded stem and disposed between the semi-cylindrical portions of the handle and connected thereto by means of a swivel joint.

2. A wrench of the character specified, comprising a handle embodying similar or like sections, each section including cheek and semi-cylindrical portions, the latter having an inner rib at its rear end, similar or like jaws pivoted between the cheek portions of the handle and having rear extensions, laterally spaced, longitudinally curved and oppositely inclined, a head slideable between the cheek portions of the handle and recessed in opposite sides to receive said extensions of the jaws and having opposed lateral flanges to engage opposite edge portions of the cheeks, a threaded stem projecting from the head, a nut within the handle engaging said threaded stem and having a swivel joint connection with the handle, and a fingerpiece at the rear end of the nut abutting the rear end of the handle and conforming to the latter.

In testimony whereof I affix my signature in presence of two witnesses.

JAMES F. BAILEY.

Witnesses:

W. H. GIBBES,
JAMES L. REID.
